UNITED STATES PATENT OFFICE.

WILLIAM H. SPENCER, OF BOGOTA, NEW JERSEY, ASSIGNOR TO I. P. FRINK INC., OF NEW YORK, N. Y., A CORPORATION OF NEW YORK.

SIGN AND METHOD FOR MAKING THE SAME.

Application filed April 17, 1924. Serial No. 707,146.

To all whom it may concern:

Be it known that I, WILLIAM H. SPENCER, a citizen of the United States, residing in Bogota, county of Bergen, and State of New Jersey, have invented certain new and useful Improvements in Signs and Methods for Making the Same, of which the following is a specification.

This invention relates to signs and methods for making the same. It is more especially related to devices of this nature in which a legend or design is arranged upon a background of contrasting character or appearance. The primary object of my invention is to provide an improved construction and an improved method for making an article of this nature.

As an illustration of the principle underlying this invention, I have shown on the drawings a preferred embodiment in the form of an illuminated sign which is preferably constructed on a base of glass or other translucent material for the purpose of enhancing its ornamental appearance and for showing the design or legend thereon in striking contrast to the surrounding background. Toward the attainment of this purpose, the present invention contemplates a sign comprising electro-plated roughened areas in conjunction with unroughened areas contiguous thereto. The method employed and the final result secured will be understood from the specification. In carrying out my invention on a base of uniform thickness, the areas to be roughened are preferably treated by sand blast or hydro-fluoric acid so that said roughened areas are depressed with respect to the unimpaired surface of the block. For the purpose of accentuating the outline of the design or legend on the sign the invention contemplates as a refinement, the electro-plating operation to form a border to the roughened areas which in its relation to the plane of the unroughened areas may be flush therewith, slightly raised with respect thereto, thickened or beaded as desired. According to the drawings, the invention has been illustrated in this respect with a raised thickened border around the design or legend.

Specific objects of invention will appear in the specification and be pointed out in the appended claims.

In the drawings, Figures 1 to 8 inclusive, illustrate successive stages in the process of

manufacture, all of said views corresponding to the line 8—8, of Figure 9.

Figure 1 is a fragmentary cross-section of the sign base as constructed of plate glass;

Figure 2 is a fragmentary section of the same after the application of a suitably prepared layer of paper corresponding in form to the design or legend to be formed on said plate;

Figure 3 is a similar fragmentary section according to which a layer of adhesive has been applied to said paper;

Figure 4 is a similar section showing the application of a protective coating of sand to the adhesive layer;

Figure 5 is a similar section after surrounding portions of the background have been removed by a sand blast;

Figure 6 is a similar section after the application to the background of a conductive layer such as a silver solution, portions of the protective covering on the design being broken away;

Figure 7 is a similar section showing the plate after removal of the protective covering;

Figure 8 is a similar fragmentary section of the finished sign on the line 8—8 of Figure 9;

Figure 9 is a plan view of a finished sign constructed according to the present invention;

Figure 10 is a similar plan view of another embodiment in its final form as exemplified in a clock dial;

Figure 11 is a fragmentary section on the line 11—11 of Figure 10;

Figure 12 is a similar fragmentary section showing an incompletely stage of the same;

Figure 13 is a fragmentary detail plan of the dial at an incompletely stage;

Figure 14 is a fragmentary plan view of another embodiment of my invention as exemplified in a clock dial; and

Figure 15 is a fragmentary section on the line 15—15, of Figure 14.

In the embodiment of my invention shown in Figures 1 to 9 inclusive, a base 1 constructed of plate glass has been operated upon to form in relief the letters indicated thereon by reference characters 2, said letters having for their upper surfaces, the residual portions of the original surface of the plate glass after portions contiguous thereto have been removed by a suitable

agency such as a sand blast or a bath of hydrofluoric acid which leaves a roughened background corresponding to the hollowed out spaces 7. According to my improved 5 method of producing this sign a protective covering is applied to portions of the upper surface of the plate glass base 1 shown in Figure 1. Said protective covering may comprise a layer 4 of paper or other suitable 10 material as indicated in Figure 2, the upper surface of said layer 4 being covered by a layer 5 of suitable binding material as shown in Figure 3. Upon this binder, may be deposited a layer 6 of sand, for example, which 15 is adapted to withstand the erosive effects of a sand blast by which unprotected areas of the plate glass base 1 may be degraded to form the hollows 7 corresponding in form to the legend or design with which the plate 20 glass base is to be marked. As shown in Figure 6, the roughened sand blasted areas of the top surface of the plate 1 are next covered by any suitable conductive layer 8 such for example as graphite solution or by 25 a coating of metallic paint which, for example, may consist of powdered graphite or similar powder in an aqueous solution of water glass as described in U. S. Patent No. 893,811 granted to Pickard under date of 30 July 21, 1908, or any other suitable coating of this nature for permanently attaching the conductive layer to the glass plate and incorporating it with said plate. As an alternative for this purpose, the roughened 35 glass plate or sand blasted letters may be coated with a chemical deposit of silver for the electrolytic deposit to be made thereon. The protective covering comprising the layers 4, 5 and 6 may then be removed from the 40 unimpaired portions of the original top surface of the plate glass as indicated in Figure 7 and the plate thus prepared suspended in a suitable solution for electro-plating the conductive layer 8. The final form of the 45 sign thus produced is illustrated in Figures 8 and 9 in which an electro-deposited layer 9 such, as for example as copper, constitutes a decorative background to the letters Exit which are formed by the smooth original 50 top surface of the plate glass base 1. From an inspection of Figures 7 and 8, it will be seen that the conductive layer 8 is preferably provided with upwardly presented marginal edges 8^a around the borders of the letters 55 2 so that when the electro-deposited layer 9 is applied thereto, a beaded relief border 10 is formed around the margin of each of said letters.

An adaptation of my invention to the construction of a clock dial, is shown in Figures 60 10 to 13 inclusive. A circular plate 11, of glass which may be clear, opaque or ground is provided with depressions to form the design in intaglio in the dial plate. According to this embodiment of my invention,

the numbers or designs with which the plate glass base 11 is to be marked, constitute those areas which are to be degraded and then built up by superposed layers of conductive material and electro-deposited 70 metal. The protective covering may be provided in the manner described in connection with Figures 1 to 9 inclusive or a suitable stencil plate 12 may be employed 75 as indicated in Figure 12, said stencil being applied to the top surface of the plate glass while the sand blast is directed against the unprotected portions of said top surface to form the depressions indicated at 13 in Figure 12. The roughened depressions thus formed are flooded with a suitable conductive solution or paint of any desired composition such as suggested above. For this purpose, the several numbers of the clock 80 dial may be connected up with the battery anode by conductive strips 14, and with each other by suitable bridge strips 15, said conductive strips being removed after the electro-plating has been accomplished and the dial removed from the bath. The dial 85 plate thus completed includes the electro-deposited layer 16 with raised beaded margins 17 forming a strikingly beautiful design.

Referring now to the embodiment shown in Figures 14 and 15 of the drawings, the figures on the clock dial may be constructed in relief and with raised beaded margins by a sequence of operations similar to those 90 described in connection with Figures 1 to 9 inclusive. Thus the roughened surface 20 of the degraded portions of the design is coated with a conductive layer 21 upon which is electro-deposited a layer of metal 22. For this purpose, a plate glass base 19 100 may be subjected to the degrading action of hydrofluoric acid or sand blast preparatory to the application of the conductive and electro-deposited layers.

I claim:

1. The method of forming a device of the character described, which method consists in forming a permanent base, in removing portions of said permanent base corresponding to the design or legend desired, in applying a conductive layer to the surface left by the removal of said base portions and in electro-plating the portions of said base to which said conductive layer has been applied.

2. The method of forming a device of the character described, which method consists in forming a roughened surface upon a permanent base to outline a design or legend thereon, in applying a conductive layer to said roughened surface and in depositing a permanent electroplated layer on said roughened surface by means of said conductive layer.

3. The method of forming a plate glass

- sign which method consists in treating one surface of a plate glass base to form a depressed roughened surface, and in permanently electroplating said depressed 5 roughened surface by means of a suitable interposed conductive layer, and in continuing the electrodeposition until a thickened border is formed thereon to accentuate the outline.
- 10 4. The method of making signs, which consists in providing a plate glass base with a roughened surface forming an outline thereon, in applying a conductive layer to said roughened surface, and in electroplating 15 said conductive layer to form a permanently attached and incorporated metal deposit on the roughened areas of said sign.
5. The method of making signs, said method consisting in roughening portions 20 of the surface of a plate glass base, in applying to said roughened portions a conductive layer adapted to form a permanently attached and incorporated portion of said base, and in electroplating said conductive 25 layer.
6. A plate glass sign having unimpaired surface portions and depressed roughened surface portions, and a metallic layer permanently attached to said depressed roughened surface portions. 30
7. The method of forming signs, said method consisting in applying a protective coating to portions of a plate glass base, in treating the portions adjacent to said protective coating to form a roughened depressed surface, in applying a conductive layer to the roughened depressed surface, said conductive layer being provided with raised borders around the margin of said protective coating, in electro-plating said conductive layer, and in removing said protective coating. 35
8. A sign constructed of translucent material and having unimpaired surface portions and roughened surface portions, and a metallic layer permanently attached to and incorporated with said roughened surface portions. 40 45

WILLIAM H. SPENCER.
